[57] CLAIM

The ornamental design for an attachment apparatus for securing an electronic device to a loose-leaf support assembly, as shown and described.

DESCRIPTION

FIG. 1 is a perspective view of an attachment apparatus for securing an electronic device to a loose-leaf support assembly showing our new design;

FIG. 2 is a perspective view thereof, the electronic device depicted by means of broken lines being shown for illustrative purposes only and forming no part of the claimed design;

FIG. 3 is a front elevational view;

FIG. 4 is a rear elevational view;

FIG. 5 is a top plan view;

FIG. 6 is a bottom plan view;

FIG. 7 is a left side elevational view;

FIG. 8 is a right side elevational view; and,

FIG. 9 is a perspective view showing an alternate position.
